DESIGN FOR A STEAM JACKETED KETTLE

Reed A. Anderson, New Kensington, Pa., assignor
to The Aluminum Cooking Utensil Company,
New Kensington, Pa., a corporation of Penn-
sylvania

Application May 16, 1934, Serial No. 51,802

Term of patent 7 years

To all whom it may concern:

Be it known that I, Reed A. Anderson, a citizen
of the United States, residing at New Kensington,
in the county of Westmoreland and State of
Pennsylvania, have invented a new, original, and
ornamental Design for a Steam Jacketed Kettle,
of which the following is a specification, refer-
ence being had to the accompanying drawing,
forming a part thereof.

The figure shown is a perspective view of a
steam jacketed kettle, embodying my new design.

I claim:

The ornamental design for a steam jacketed
kettle, as shown.

REED A. ANDERSON.
